The National Cash Register Company, Dayton,
Ohio, a corporation of Maryland

Original application July 27, 1931, Serial No.
553,329. Divided and this application November
8, 1933, Serial No. 697,116

5 Claims. (Cl. 235—138)

This invention relates to improvements in registers, ticket-issuing machines and the like of the type shown and described in Letters Patent of the United States No. 1,816,263, issued on July 18, 5 1931 to William H. Robertson and is a division of the application for United States Letters Patent of William H. Robertson, Serial No. 553,329, filed July 27, 1931.

One object of this invention is to provide a 10 novel and absolutely positive transfer or carrying mechanism for a totalizer adapted to be used in machines of the above mentioned type.

Another object of this invention is to provide 15 novel means cooperating with the transfer or carrying mechanism to positively restore such mechanism to its normal position when it has been moved out of its normal position through overthrowing of the totalizer wheels.

With these and incidental objects in view, the 20 invention consists of certain novel features of construction and combinations of parts, the essential elements of which are set forth in appended claims and a preferred form of embodiment of which is hereinafter described with reference to the drawing which accompanies and forms part 25 of this specification.

Of said drawing:

Fig. 1 is a detail view of the upper totalizer 30 showing the transfer mechanism in normal position.

Fig. 2 is a detail view of a part of the transfer mechanism for the upper totalizer, showing the transfer arm in retracted position.

Fig. 3 shows the same mechanism as Fig. 2 but 35 with the transfer pawl tripped.

Fig. 4 is a detail view of the device for restoring the transfer pawl to normal when it is tripped by overthrowing the totalizer.

Fig. 5 is a detail view of the Geneva transfer 40 mechanism for the overflow totalizer wheels of the upper totalizer.

Fig. 6 is a front view of the totalizer showing the actuator and the alining device associated therewith.

45 GENERAL DESCRIPTION

The machine disclosed in the parent application, of which this case is a division, is adapted for recording postage and for printing and issuing 50 gummed postage labels for use on first, second, third and fourth-class mail. It is particularly adapted for use where heavy packages of different sizes and weights have been weighed to determine the amount of postage required.

55 The machine is provided with two separate and

independent totalizers, one of which totalizers, namely, the one forming the subject matter of this divisional application, is located in that position of the machine usually occupied by indicators, there being no indication provided in the machine shown in the parent application. This totalizer is a reading totalizer and is constantly visible through a sight opening in the cabinet. The purpose of this totalizer is to accumulate the amount of the postage issued by the machine. 10 This totalizer cannot be reset to zero and movement of the usual control lever to the read position in the machine of the parent application disables the engaging mechanism for this reading totalizer. Consequently this totalizer can be engaged with its actuators only when the machine is set to add.

The main features of this divisional application relate particularly to the transfer or carrying mechanism of this totalizer and also to the 15 alining mechanism associated with the totalizer.

This totalizer, in the parent case, has been designated as the upper totalizer and for this reason will be so termed in this divisional application.

25 The same reference numbers as are applied to the various parts of the parent application are used in the present case.

DETAILED DESCRIPTION

30

Upper totalizer

The upper totalizer includes a series of reading totalizer wheels 141, 142 and 143 (Figs. 1, 2, 3 and 6), rotatably mounted on a rod 144 carried between a pair of totalizer frames 149 and 150 loosely mounted on a rod 151 extending between the side frames (not shown) of the machine. Gears 152, one secured to the side of each of the wheels 141 and 142, are adapted at the proper time to be brought into engagement with totalizer actuator gears 138 so that the amount corresponding to the amount set up on the keyboard may be added into the upper totalizer, 40 as is fully illustrated and described in the parent case above referred to.

The mechanism for engaging the upper totalizer wheels with and disengaging said wheels from the actuators 138 will not be shown nor described in detail in this divisional application, it being thought sufficient to state here that it is accomplished by oscillation of a cam shaft 155 which in turn receives its motion from the main drive shaft of the machine.

55

An aliner is provided to aline the actuators 138 in their adjusted positions after they have been set. This aliner is normally in engagement with said actuators 138. It is disengaged therefrom before the actuators are adjusted and reengaged therewith immediately after said actuators have been set and before the totalizer is disengaged from the actuators.

This aliner includes an aliner bar 145 (Figs. 2 and 6) secured to a bail 146 carried by a pair of arms 147 secured on a shaft 148 journaled in the machine side frames. This shaft 148 is rocked clockwise to disengage the aliner 145 from the actuators 138 and then counter clockwise to re-engage said aliner with said actuators at the proper time as is fully described in the parent case.

Transfer mechanism for the upper totalizer

20 A transfer or carry mechanism is provided to advance the totalizer wheel of higher order one step of movement when the wheel 142 of lower order passes from "9" to "0". This mechanism will now be described in detail.

25 Secured to each of the gears 152 (Figs. 1, 2, 3 and 6) for each of the wheels 141 and 142 is a ratchet 182 with which cooperates a transfer pawl 183 pivotally carried on an arm 184 of a transfer lever 185 pivoted on the shaft 151. A pair of rollers 186 carried on the other arm 187 of each of the levers 185 cooperates with one of a series of transfer cams 188 fast on the shaft 155. The pawls 183 normally cooperate with the ratchets 182 in the manner illustrated in Fig. 1, to lock the totalizer wheels 142 so that they may not be manipulated.

30 As before stated, the shaft 155 is oscillated first clockwise and then counter clockwise to normal. On its clockwise movement the cams 188 rock the levers 185 successively, beginning with the highest order wheel, which in this particular case is the dollar wheel, counter clockwise to withdraw the transfer pawls 183 from cooperative relationship with their respective ratchets. The lever 185 for the dollar wheel is rocked counter clockwise first, followed by the lever 185 for the dime wheel and finally the levers 185 for the penny and half-cent wheels follow. It will be noted that only three cams 188 are provided whereas referring to Fig. 6 it will be noted that four levers 185 are provided. The levers 185 for the penny wheel and for the half-cent wheel are secured together by a hub 189 and therefore rock in unison. There is no cam provided for the lever 185 in the one-half cent bank. A pawl 183 (Fig. 6) carried by the arm 184 for this bank serves only as a locking pawl to lock the one-half cent totalizer wheel 141 against manipulation. It will be noted by referring to Fig. 6 that the particular pawl 183 associated with the one-half cent totalizer wheel is secured to its arm 184 by a pin or rivet 190.

35 After the levers 185 are all rocked counter clockwise, withdrawing the pawls 183 from cooperative relation with their respective ratchets, the totalizer having been engaged with the actuators 138 at approximately the same time, the totalizer wheels 141 and 142 are advanced according to the set-up on the keyboard. If during this adding operation any particular totalizer wheel passes from "9" to "0", the transfer mechanism is tripped to add one in the totalizer wheel of next higher order.

40 This tripping mechanism includes a tripping tooth 191 (Figs. 1 and 4) secured to the left-

5 hand side (as viewed in Fig. 6) of each of the three lower order totalizer wheels 141 and 142. As a lower order totalizer wheel passes from "9" to "0" the tripping tooth 191 wipes by a nose 192 on one arm 193 of a lever 194 pivoted on a rod 195 carried by the upper totalizer frames 149 and 150, rocking the lever 194 clockwise. A stud 196 on the other arm 197 of the lever 194 projects through an open slot 198 in an arm 199 of a three-armed lever 200 pivotally carried on the 10 lever 185. The rounded end of an arm 201 of the lever 200 is embraced by a bifurcated arm 202 of the pawl 183. Clockwise movement of the lever 194 rocks the three-armed lever 200 counter clockwise and, by the rounded arm 201, rocks 15 the arm 202 and consequently the pawl 183 clockwise to the positions in which these parts appear in Fig. 3.

Now, when the cam 188 for the particular bank or transfer lever 185 appearing in Figs. 2 and 3, 20 rocks the lever 185 clockwise, obviously the pawl 183 engages the ratchet 182 (see Fig. 3) secured to the next higher order totalizer wheel, and as the lever 185 rocks clockwise the pawl 183 advances the ratchet 182 and its associated totalizer wheel 142 one step of movement. At the end of the clockwise or restoring movement of the lever 185 a stud 203 projecting from the arm 184 of said lever 185 comes into contact with the pawl 183 pressing this pawl against the ratchet 182 30 in such a manner as to lock the ratchet and consequently the totalizer wheel 142 against movement in either direction.

As the transfer is effected, that is, as the lever 185 carries the pawl 183 clockwise to advance 35 the totalizer wheel 142, the pawl 183 is rocked counter clockwise about its pivot on the arm 184 thus restoring the pawl to its untripped position. The pawl 183, rocking counter clockwise, rocks the three-armed lever 200 clockwise to normal, 40 and by the slot 198 and stud 196 rocks the lever 194 counter clockwise to its normal position. The lever 194, the lever 200 and the pawl 183 are held either in their normal positions or in their tripped positions by an aliner 204 pivotally carried on the 45 arm 184 of the lever 185, engaging one of two notches 205 or 206 in the end of an arm 207 of the three-armed lever 200. A spring 208 constantly presses the pawl 204 into cooperative relation with one of said two notches 205 or 206. 50

To prevent movement of the totalizer wheels when the locking and transfer pawls 183 are out of engagement with the ratchets 182, retaining pawls 209 are pivoted on the rod 195 and cooperate with the ratchet 182 for each of the totalizer 55 wheels 141 and 142.

Due to the fact that the one-half cent key (not shown) occupies the five position in its bank, whenever this key is depressed and the machine is operated the one-half cent totalizer wheel is 60 rotated five steps or spaces. Therefore it can be seen that every other time the machine is operated with the one-half cent key depressed, the tripping tooth 191 attached to the one-half cent key wheel 141 trips the transfer to the penny bank wheel 142 resulting in the addition of "1" 65 to this penny totalizer wheel 142.

70 Due to lost motion which may reside in the train of gears comprising the full differential mechanism as shown in the parent case, the totalizer wheels 142 may be slightly overthrown particularly when the machine is operated rapidly. For instance, suppose the totalizer wheels were setting at "1" and "8" was added thereon. In 75 this case the wheel rotating rapidly in a clock-

wise direction (Fig. 1) might overthrow sufficiently to carry the tripping tooth 191 into contact with the nose 192 on the lever 194 thus rocking this lever and tripping the pawl 183. The totalizer wheel would then be restored to its proper position by the retaining pawl 209 or by the totalizer actuator 138, leaving the transfer tripped. Less than one-half tooth space overthrow of the actuator 138 has been found sufficient to overthrow the totalizer wheel sufficiently to trip a transfer. Therefore mechanism is provided in the present machine to restore the transfer mechanism to its normal position when it is tripped by overthrowing the totalizer wheels in the above described manner. This mechanism will now be described.

The above mentioned restoring mechanism includes a restoring tooth 215 (Fig. 4) integral with the tripping tooth 191. This tooth 215 is adapted to cooperate with a nose 216 on the arm 197 of the lever 194. The tooth 215 occupies the position in which it is shown in Fig. 1 when "9" is standing on the totalizer wheel. It will be noted from Fig. 1 that less than one-half tooth space movement of the wheel will cause 191 to strike 192. If the totalizer wheel is overthrown a half step or less so that the tooth 191 strikes the nose 192 with a sudden impact, it rocks the lever 194 clockwise, and the tooth 215 moves beyond the nose 216 toward, but not all the way into the position in which it is shown in Fig. 4. At this time the next tooth space of the actuator is not aligned with the aliner 145, and therefore when the aliner 145 (Figs. 2 and 6) is moved into engagement with the proper tooth space on the actuator 138 and if said actuator has been overthrown the aliner 145 moves said actuator backwardly or clockwise to its proper position thus rotating the totalizer gear 152 associated therewith and its corresponding totalizer wheel 142 backwardly or counter clockwise to their normal positions. The one-half step or less overthrow of the wheel 142 is not sufficient to cause the next ratchet tooth of the ratchet wheel 142 to pass from under the pawl 209, and therefore this pawl will not interfere with the return movement of the totalizer wheel. On the other hand it will assist in such return of the totalizer wheel. When the aliner 145 returns the actuator 138, the tooth 215 on its backward movement wipes by the nose 216 and rocks the lever 194 backwardly counter clockwise to its normal position. This provides a positive return of the totalizer wheel when it is accidentally overthrown.

If the transfer is authentic, that is, not caused by an overthrow, the tooth 191 together with the ratchet 192 and the totalizer wheel 142 are moved one full step, in which case the aliner 145 is re-engaged with the proper tooth space of the actuator 138 and the totalizer wheel 142 is not rotated backwardly since the retaining pawl 209 moves into the next succeeding notch of the ratchet 182. It will be noted that the nose 192 on the arm 193 is offset from the arm 197 as is clearly shown in Fig. 6, and that likewise the tooth 191 which is in line with the nose 192 is offset from the tooth 215 which is in the same plane with the nose 216. Thus it can be seen that during the normal position of the totalizer wheel 142 the tooth 191 cooperates only with the nose 192 and the tooth 215 cooperates only with its associated nose 216.

The usual Geneva transfer mechanism disclosed in Figs. 5 and 6 is provided to transfer or carry into the overflow totalizer wheels 143.

This transfer mechanism includes the usual

disk 217 carrying a single tooth 218 adapted to cooperate with a gear 219 on the rod 195. The disk 217 is secured to the totalizer wheel of lower order and when this wheel has completed one rotation and passes from "9" to "0", the tooth 218 cooperates with the gear 219 to advance this gear one step which gear 219 also meshes with a gear 220 on the next higher order totalizer wheel, thus advancing the latter wheel one step of movement.

Since the various movements of the transfer elements have been given above in the detailed description of the transfer mechanism it is not thought necessary to again repeat the operation of these elements.

While the forms of mechanisms herein shown and described are admirably adapted to fulfill the objects primarily stated, it is to be understood that it is not intended to confine the invention to the forms of embodiment herein disclosed, for it is susceptible of embodiment in various forms all coming within the scope of the claims which follow.

What is claimed is:

1. In a machine of the class described, the combination of a totalizer; a transfer operating pawl normally in engagement with a totalizer wheel to lock the same against movement; an operating lever supporting said pawl and normally maintaining it in its locking position; means to move the lever to disengage the pawl from the wheel, said means also being adapted to restore the lever; a device carried by the lever and adapted to move the pawl into a position to turn the wheel one step when said lever is restored to its normal position; a member connected to said device and adapted to operate the latter; and means connected to a totalizer wheel of next lower order to operate said member.

2. In a machine of the class described, the combination of a totalizer; an actuator therefor; a pawl normally engaging a totalizer wheel to lock the same in its normal position; a tripping member associated with a wheel of next lower order; means intermediate the tripping member and the pawl to move the pawl into a position to effect a transfer; an alining device cooperating with the actuator to positively aline the actuator and the totalizer wheel; and means on the tripping member and operable upon an operation of the actuator alining means to operate said intermediate means reversely to restore them to their normal positions when a wheel has been overthrown in the act of transferring.

3. In a machine of the class described, the combination of a totalizer; a transfer pawl adapted to turn the totalizer wheel to effect a transfer and normally in a position to lock the wheel with which it is associated; mechanism to move the pawl into position to effect a transfer; and a single member associated with the wheel of next lower order for operating said mechanism and for restoring said mechanism to its normal position when the totalizer wheel is overthrown during the act of transferring.

4. In a machine of the class described, the combination of a totalizer; normally ineffective means to effect a transfer; means on the totalizer to render the normally ineffective means effective; means to restore the totalizer when said totalizer is overthrown; and means on the second mentioned means to restore the normally ineffective means to ineffective position when the latter has been rendered effective by overthrowing the totalizer.

5. In a machine of the class described, the combination of a totalizer; a transfer operating member normally locking the totalizer wheel against movement; operating means for said member and normally maintaining it in its locking position; means to move said operating means to render said transfer operating member ineffective, said last mentioned means also being adapted to restore said operating means; a device associated

with said operating means and adapted to move the transfer operating member into position to turn the wheel one step when said operating means is restored to its normal position; a pivoted member connected to said device and adapted to operate the latter; and means associated with a wheel of next lower order to operate said pivoted member. 5

WILLIAM H. ROBERTSON.
